US0D1057723S

(12) **United States Design Patent** (10) **Patent No.:** **US D1,057,723 S**
(45) **Date of Patent:** **** Jan. 14, 2025**

(54) **DEVICE COVER**

(71) Applicant: **Amazon Technologies, Inc.**, Seattle, WA (US)

(72) Inventors: **Tim Wall**, Mill Valley, CA (US); **Jeffrey Philip Infante**, Sunnyvale, CA (US)

(73) Assignee: **Amazon Technologies, Inc.**, Seattle, WA (US)

(**) Term: **15 Years**

(21) Appl. No.: **29/924,662**

(22) Filed: **Jan. 19, 2024**

Related U.S. Application Data

(63) Continuation of application No. 29/845,158, filed on Jul. 5, 2022, now Pat. No. Des. 1,019,657.

(51) **LOC (15) Cl.** **14-02**

(52) **U.S. Cl.**

USPC **D14/440**

(57) **CLAIM**

The ornamental design for a device cover, as shown and described.

DESCRIPTION

FIG. 1 is a front perspective view of a device cover in a closed state;

FIG. 2 is a back perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof;

FIG. 9 is a first opened state perspective view thereof; and,

FIG. 10 is a second opened state perspective view thereof.

1 Claim, 10 Drawing Sheets
